(57) **CLAIM**

The ornamental design for a rifle as shown and described.

DESCRIPTION

FIG. 1 is a left side perspective view of a rifle in accordance with a first embodiment of the present design;

FIG. 2 is a right side perspective view thereof;

FIG. 3 is a front view thereof;

FIG. 4 is a right side view thereof;

FIG. 5 is a left side view thereof;

FIG. 6 is a top view thereof;

FIG. 7 is a bottom view thereof;

FIG. 8 is a rear view thereof;

FIG. 9 is a rear perspective view of a rifle in accordance with a second embodiment of the present design;

FIG. 10 is a right side perspective view thereof;

FIG. 11 is a front view thereof;

FIG. 12 is a right side view thereof;

FIG. 13 is a left side view thereof;

FIG. 14 is a top view thereof;

FIG. 15 is a bottom view thereof; and,

FIG. 16 is a rear view thereof.

The broken lines in the drawings illustrate portions of the rifle that form no part of the claimed design.
